UNITED STATES PATENT OFFICE.

HARROD E. CULLY, OF DAYTON, OHIO.

MACHINE FOR STAMPING AND DELIVERING TRANSFERS.

1,177,493.

Specification of Letters Patent. Patented Mar. 28, 1916.

Application filed March 9, 1915. Serial No. 13,267.

To all whom it may concern:

Be it known that I, HARROD E. CULLY, a citizen of the United States, residing at Dayton, in the county of Montgomery and State of Ohio, have invented new and useful Improvements in Machines for Stamping and Delivering Transfers, of which the following is a specification.

An object of the invention is to provide a machine preferably adapted for use on street railway cars and the like, and which, when properly operated, will feed into printing position, print or stamp a transfer, sever the same from a body or roll of paper and deliver the same to the conductor or person who is to receive the transfer.

The invention contemplates, among other features, the provision of a machine adapted to be operated by the usual conductor or similar officer on a street railway or other transportation line and which will feed one end of a roll of previously prepared or stamped paper into printing position, cause the same to be stamped with the date of issuance of the transfer and the time, cut the stamped transfer from the body of the roll of paper and cause the same to be delivered to the conductor or person for whom the transfer is issued, the various operations of the machine described herein being accomplished by one movement of the conductor.

In the further disclosure of the invention reference is to be had to the accompanying drawings, constituting a part of this specification, in which similar characters of reference denote corresponding parts in all the views, and in which:

Figure 1 is a perspective view of the machine; Fig. 2 is a fragmentary vertical sectional view taken through the machine; Fig. 3 is a horizontal transverse sectional view taken on the line 3—3 in Fig. 2; Fig. 4 is a horizontal sectional view taken on the line 4—4 in Fig. 2; Fig. 5 is a vertical sectional view taken on the line 5—5 in Fig. 2; Fig. 6 is a vertical transverse sectional view taken on the line 6—6 in Fig. 2; and Fig. 7 is a face view of one of the transfers.

Referring more particularly to the views, I disclose a casing 10 in which is suitably supported to rotate a paper supply 11 in the nature of a roll, the paper on the roll being in the nature of a continuous strip, preferably suitably printed, with the name of the street railway company and other matter,

and being divided into portions which may be conveniently called transfer portions and which are subsequently adapted to become transfers when the time and date of issuance of the transfer is stamped thereon. Each transfer portion is provided with spaces 12 in which the date and time or some other convenient matter can be suitably stamped. A portion of the paper being unwound from the roll, the same passes upwardly in the casing over a roller 13 therein and then passes around a roller 14 to pass between the roller 14 and a roller 15, said rollers 14 and 15 being suitably journaled in the casing, with the roller 14 preferably affixed to a shaft 16 which is journaled in the casing.

Suitably mounted within the casing is a bed or frame 17 upon which may be placed a plate 18 and which, if the roll is blank and does not have the name of the company thereon, may have a suitable printing form which will, when the paper is pressed against the same, convey its printing form or impression to the paper so as to print or form the transfer, it being understood, however, that the transfer can be as shown, with the name of the company printed thereon prior to forming the roll of paper. A platen 19 is supported by suitable arms 20 which are pivoted to the platen and which are pivoted to suitable arms or levers 21 eccentrically pivoted to a disk 22 carried on a shaft 23 journaled in the casing, supporting arms 24 being pivoted to the arms or levers 21 and to a wall of the casing. Now it will be seen that rotation of the disk 23 will result in the platen 19 being advanced toward the bed or frame 17 and the plate 18, if the same is mounted upon the bed. At the upper end of the bed there is provided a cutting member in the nature of a horizontal blade 25, the upper end of the platen being provided with an offset portion 26 for a purpose that will be hereinafter more fully described.

Arranged to operate around suitable rollers 27, one of which, numbered 28, I will term a main roller, said rollers being journaled in the casing, is an endless printing ribbon 29 and which passes between the platen and the bed and plate. Now it will be clearly seen that when an end of the strip of paper on the roll, passing between the rollers 14 and 15, is arranged to pass between the platen and ribbon, the operation of the platen, and which causes the platen to press

against a face of the paper, will press the paper against the printing form or plate, thus resulting in the impression of the printing form being transferred to the paper.

5 A series of exteriorly arranged operating knobs 30 are provided for the casing and as mentioned lie exteriorly thereof, the innermost knob having a preferably solid shaft 31 passing through the casing and connecting with a printing disk 32, with the next operating knob having a tubular shaft 33 connecting with a printing disk 34 within the casing, the solid shaft passing through the hollow shaft so that the turning of one 10 knob will rotate the printing disk to which its shaft is connected without effecting the other printing disk. The printing form or plate 18 is provided with openings 35 through which the printing disk 34 can be seen and through which, in fact, the disks will project, so that the form upon the disks will be impressed in the spaces 12 of the paper when the platen 19 is operated to exert pressure on the paper and press it against 15 the ribbon and which ribbon is interposed between the paper and the printing disks and form.

A rod or other suitable member 36 has connection with an arm 37 projecting from the disk 22, said rod passing exteriorly of the casing and connecting with a suitable operating lever or foot lever (not shown) to be actuated by the conductor and which, resulting in the rotation of the disk 22 will actuate the platen 19 as mentioned heretofore, a suitable spring 38 being associated with the rod and supported upon the bottom of the casing in order to return the rod 36 to its initial position when the foot lever has 20 been operated. In order to feed the free end of the strip or roll of paper into position between the platen and printing form there is provided a chain 39 which passes over a sprocket 40 loosely mounted upon the shaft 16, a pawl 41 being mounted on the sprocket and operating over teeth upon a suitable ratchet wheel 42 which is keyed to the shaft 16. One end of the chain carries a weight 43 and the other end of the chain 25 is connected by means of a cord 44 with an arm 45 connected to the shaft 23, it being understood that the sprocket 40 is of small diameter and that the arm 45 can have a large swinging radius in order that sufficient movement can be obtained to feed the paper, as will be hereinafter more fully set forth.

The roller 15 is keyed upon the shaft 46 journaled in the casing and the shaft carries a toothed wheel 47 over which operates an endless chain 48 connecting with a toothed wheel 49 carried by a shaft 50 journaled in the casing and supporting the main roller 28 which is in rotating contact with 30 a roller 51 journaled in the casing, said roller

51 being in contact with a roller 52 and which in turn is in contact with a roller 53, the rollers 51, 52 and 53 being substantially similar, with the rollers 52 and 53 also suitably journaled in the casing and adapted to receive a quantity of ink from a suitable supply 54. Now it will be seen that when the roller 15 is actuated, due to the paper passing between the roller 15 and the roller 14, the chain 48 connecting with the toothed wheel 49 will result in rotation of the roller 28 to operate the endless ribbon and which passing between the rollers 28 and 51 will thus be inked, the ink coming from the rollers 52 and 53 which receive the ink from the supply 54.

Assuming that the device is in the position shown and that the paper has been fed down between the platen and the printing form so that its lower end will lie in position to pass through a chute 55 extended to form a tray 56 exteriorly of the casing, a downward pressure upon the trip lever resulting in a downward pull upon the rod 36 will rotate the shaft 23 and thus also the disk 22. The rotation of the disk 22 will cause the platen 19 to press against the paper between the platen and the printing form and printing disks so that the impression upon the printing disks and which have been previously rotated to bring the desired date and time into the openings in the printing forms, will be impressed upon the paper, while at the same time the offset portion 26 of the platen, bearing against the paper, will press the upper end of the paper against the knife blade, thus severing the paper from the main body and forming the transfer. When the platen returns to initial position the transfer will slide down the chute 55 on to the tray 56 and is then ready to be handed to the passenger. The rotation of the shaft 23 causes the arm 45 to swing upwardly, thus slackening the chain 39. The sprocket 40 will now rotate freely on the shaft due to the weight 43 exerting a downward pull on the outer end of the chain and when the rod 36 is returned to initial position by the spring 38 the opposite rotation of the shaft 23 will exert a downward pull on the arm 45, thus pulling on the chain 39 and acting upon the pawl and ratchet mechanism mentioned so as to impart rotation to the roller 14 and feed a new strip of the paper downwardly between the platen and the printing form, while the platen is returned to initial position.

Thus it will be seen that each time that the foot lever is operated by the conductor a transfer will be stamped, severed from the main body or supply and delivered exteriorly of the casing, while the release of the foot lever will result in a new strip of the paper being fed into position to form a new transfer which, upon a subsequent

operation of the foot lever, will be punched or stamped, cut from the main body of supply and delivered to the tray 56. At the same time the ribbon 29 will be continuously inked by the rollers 51, 52 and 53 in the manner mentioned heretofore and which will be suitably rotated due to their contact with the ribbon and which is interposed between the roller 28 and the roller 51, said roller 28 receiving its rotation from the rotation of the roller 15 and which has the toothed wheel 47 rigid on the same shaft 46 connected by a chain 48 to the toothed wheel 49 rigid upon the shaft 50 carrying the roller 28.

The casing 10 is preferably made of two sections 57 which can be conveniently detachably united by a suitable fastening means 58 and a portion 59 of the casing is preferably made transparent in order that the conductor can see the printing disks and so rotate the operating knobs as to bring the proper printing matter on the disks into the openings in the plate, it being understood, however, that the operating knobs can be suitably marked on their surfaces and will indicate to the conductor the adjustment that is necessary in order that the desired date and time can be stamped upon the transfer. As mentioned heretofore, the supply of paper can be either initially formed into transfer portions by having the name of the company and other suitable data printed thereon, leaving blank spaces for the date and time, or the supply can be a blank roll which is to receive all of the printing in the operation of the machine when the plate 18 is used with a printing form thereon.

Having thus described my invention, I claim:

1. A machine of the class described comprising a casing, a pair of rollers journaled interiorly of the casing near the top thereof of, a guide roller spaced from the said pair of rollers, a strip roller mounted in the casing near the bottom thereof and having a strip trained over the guide roller and between the pair of rollers, a delivery chute opening through the front of the casing and receiving the strip from between the pair of rollers, a movable platen located between the chute and the pair of rollers and adapted to move a stretch of the strip, a stationary bed arranged forwardly of the platen, inking means movable over the bed, printing mechanism co-operative with the inking means and engaged by a strip, a pair of toggles mounted within the case and acting upon the platen to advance the strip into contact with the printing mechanism, an eccentric mounted between the toggles and having arms eccentrically pivoted thereto and also pivoted with the toggles for operating the same, a connection between the eccentric and one of the pair of rollers for intermittently rotating the same on actuating the toggles, and means for turning the eccentric.

2. A machine of the class described comprising a casing, a pair of rollers journaled interiorly of the casing near the top thereof, a guide roller spaced from the said pair of rollers, a strip roller mounted in the casing near the bottom thereof and having a strip trained over the guide roller and between the pair of rollers, a delivery chute opening through the front of the casing and receiving the strip from between the pair of rollers, a movable platen located between the chute and the pair of rollers and adapted to move a stretch of the strip, a stationary bed arranged forwardly of the platen, inking means movable over the bed, printing mechanism co-operative with the inking means and engaged by the strip, a pair of toggles mounted within the case and acting upon the platen to advance the strip into contact with the printing mechanism, an eccentric mounted between the toggles and having arms eccentrically pivoted thereto and also pivoted with the toggles for operating the same, a connection between the eccentric and one of the pair of rollers for intermittently rotating the same on actuating the toggles, and means for turning the eccentric.

2. A machine of the class described comprising a casing, a pair of rollers journaled interiorly of the casing near the top thereof, a guide roller spaced from the said pair of rollers, a strip roller mounted in the casing near the bottom thereof and having a strip trained over the guide roller and between the pair of rollers, a delivery chute opening through the front of the casing and receiving the strip from between the pair of rollers, a movable platen located between the chute and the pair of rollers and adapted to move a stretch of the strip, a stationary bed arranged forwardly of the platen, inking means movable over the bed, printing mechanism co-operative with the inking means and engaged by the strip, a pair of toggles mounted within the case and acting upon the platen to advance the strip into contact with the printing mechanism, an eccentric mounted between the toggles and having arms eccentrically pivoted thereto and also pivoted with the toggles for operating the same, a connection between the eccentric and one of the pair of rollers for intermittently rotating the same on actuating the toggles, and means for turning the eccentric.

3. A machine of the class described comprising a casing, a pair of rollers journaled interiorly of the casing near the top thereof, a guide roller spaced from the said pair of rollers, a strip roller mounted in the casing near the bottom thereof and having a strip trained over the guide roller and between the pair of rollers, a delivery chute opening through the front of the casing and receiving the strip from between the pair of rollers, a movable platen located between the chute and the pair of rollers and adapted to move a stretch of the strip, a stationary bed arranged forwardly of the platen, inking means movable over the bed, printing mechanism co-operative with the inking means and engaged by the strip, a pair of toggles mounted within the case and acting upon the platen to advance the strip into contact with the printing mechanism, an eccentric mounted between the toggles and having arms eccentrically pivoted thereto and also pivoted with the toggles for operating the same, a connection between the eccentric and one of the pair of rollers for intermittently rotating the same on actuating the toggles, and means for turning the eccentric.

the eccentric to move the platen away from the bed.

4. A machine of the class described comprising a casing, a pair of rollers journaled 5 interiorly of the casing near the top thereof, a guide roller spaced from the said pair of rollers, a strip roller mounted in the casing near the bottom thereof and having a strip trained over the guide roller and between 10 the pair of rollers, a delivery chute opening through the front of the casing and receiving the strip from between the pair of rollers, a movable platen located between the chute and the pair of rollers and adapted to 15 move a stretch of the strip, a stationary bed arranged forwardly of the platen, inking means movable over the bed, printing mechanism coöoperative with the inking means and engaged by the strip, a pair of toggles mounted within the case and acting upon 20 the platen to advance the strip into contact 25 with the printing mechanism, an eccentric mounted between the toggles and having arms eccentrically pivoted thereto and also pivoted with the toggles for operating the same, a connection between the eccentric and one of the pair of rollers for intermittently rotating the same on actuating the toggles, a pull rod peripherally pivoted to the eccentric for moving the same to operate the 30 toggles, a spring member acting upon the pull rod to automatically lift the same for reversing the movement of the eccentric to move the platen away from the bed, and manually operable means for changing the 35 printing mechanism.

In testimony whereof I affix my signature in presence of two witnesses.

HARROD E. CULLY.
